2 SHEETS—SHEET 2.

UNITED STATES PATENT OFFICE.

WILLIAM KORTKAMP, OF HILLSBORO, ILLINOIS.

MINE-DOOR-OPERATING MECHANISM.

1,413,335.

Specification of Letters Patent. Patented Apr. 18, 1922.

Application filed September 30, 1921. Serial No. 504,352.

To all whom it may concern:

Be it known that I, WILLIAM KORTKAMP, a citizen of the United States of America, and resident of Hillsboro, in the county of 5 Montgomery and State of Illinois, have invented certain new and useful Improvements in Mine-Door-Operating Mechanism, of which the following is a specification.

This invention relates to mine trap door 10 operating mechanism effective to open and close the door, the said invention having for an object the provision of novel means whereby the door may be operated from a distance from the door aggregating from 15 one hundred to two hundred feet, according to the requirements in practice.

A further object of this invention is to produce a door operating mechanism which may be maintained in positions clear of obstructions that are very common in coal 20 mines, and in which operating parts of the mechanism may be protected or housed to prevent their being fouled by the accumulation of foreign substances or rubbish.

25 A still further object of this invention is to produce novel mine door operating mechanism effective to open either a single or double door, and in which provision may be made for operating doors at curves, as will 30 presently appear.

A still further object of this invention is to produce a mine door operating mechanism in which the weight of cars traveling on a track may be communicated evenly to 35 the door operating links and levers to avoid undue shock and vibration as the parts are actuated.

With the foregoing and other objects in view, the invention consists in the details of 40 construction, and in the arrangement and combination of parts to be hereinafter more fully set forth and claimed.

In describing the invention in detail, reference will be had to the accompanying 45 drawings forming part of this application wherein like characters denote corresponding parts in the several views, and in which—

Figure 1 illustrates a view in side elevation of a track with a door operating mechanism embodying the invention applied thereto, the door being shown in section;

Figure 2 illustrates a plan view of the said mechanism with the door in horizontal 55 section;

Figure 3 illustrates a perspective view of fragments of the operating mechanism;

Figure 4 illustrates an enlarged detailed view of parts of the operating mechanism;

Figure 5 illustrates a sectional view on 60 the line 5—5 of Fig. 4;

Figure 6 illustrates a view in elevation showing how the mechanism can be housed to obviate the accumulation of foreign substances; and

Figure 7 illustrates a sectional view thereof.

In these drawings 10, 11 and 12 denote track sections, the sections 10 and 12 being at such remoteness with respect to the section 11 as to cause the operation of the door when the car has reached a predetermined distance from the door. The rails and operating mechanism are shown as broken away so that the door operating mechanism or 75 that part thereof that is actuated by the weight of the car, may be stationed at arbitrary distances from the door. The main door operating shaft 13, which is actuated by the weight of the car, is journaled in 80 bearing brackets 14 which may be supported on cross ties 15 or other appropriate foundations, and these bearing brackets may be increased or diminished in number, according to the length of the shaft employed. Obviously, this shaft may be supplied with 85 universal joints such as 15' if the shaft is employed on curves, but this is an obvious detail of construction which one skilled in the art may employ.

The track, in the present embodiment of the invention, is guarded by a mine door 16 hinged to a post or frame 17, as is ordinarily the case, and the door has a link 18 connected to it by the mountings 19. The end 90 of the link remote from the door is pivotally connected to an arm 20, and the said arm is pivotally connected to or mounted on a post or bracket 21 in order that the said arm may swing horizontally from the position shown in full lines in Fig. 2 to the dotted line position thereof in the same figure. The arm 20 has a bracket 22 extending outwardly from one side, and this bracket is pivotally connected to another 100 arm 23 which latter arm is carried by the shaft 13, in order that it may be oscillated to communicate motion to the door. The shaft 13 may have yokes 24 attached to it which normally extend inwardly, that is to 105 say, when the door is closed, they will project toward the track, and these yokes are supplied with weights 25 which are intended to overcome gravity and friction of the

gate operating mechanism for returning the parts to a closed position automatically for closing the door after a car has passed the gate. The gate operating mechanism is under the control of the weight of the car until it passes the gate, and the gate is held open against the action of the weights until the gate is clear.

The shaft 13 is oscillated by the weight of the cars when passing over the track, through the means of levers 26 and 27 which are assembled with the inner end of the lever 27 pivotally connected to a base or tie on a pivot 28. The pivot 26 is mounted at one end on a stud or pivot 29 which is anchored in one of the cross ties. The opposite end of the lever 26, or what may be termed the outer end thereof, is connected to the lever 27 between its ends by a pivot 30. The lever 26 has a post 31 secured to it, and the said post carries a tread engaging bar 32 which extends parallel with one rail and normally has its upper edge above the top of the rail. This tread bar is in position to be engaged by the wheel of the car or rolling stock which passes over the rail, in order that the tread bar may be depressed to oscillate the lever 26. The tread bar is jointed, as shown at 34, by a hinge, and one end of the said tread bar is pivoted, as at 35, to a rail or the like, which will retain it in operative relation to the rail. The lever 27 has a post 36 carrying a tread bar 37 in operative relation to the other rail, and the said tread bar 37 may be of the same general construction and arrangement as the tread bar 32, and when a car travels along the rail and depresses the tread bars, the weight of the car will be communicated to the levers uniformly and without undue vibration, since the car first passes up the inclined portions 40 of the said tread bars. A link 41 is pivotally connected to the lever 27, and this link 41 is pivotally connected to an arm 42 secured to the shaft 13, and hence, it will rock the oscillating arm 42 and rock the shaft 13 to a degree which will cause the arm 23 to move outwardly to the dotted line position shown in Fig. 2 to open the gate, whereas the weights will return the parts to their normal position after the weight has been removed from the tread bars.

Two sets of levers 26 and 27 and parts associated therewith, by which the weight of the car is communicated to the shaft, are provided on each side of the gate, but as these parts are duplicated, a description of one set will, it is thought, suffice as a disclosure to enable one skilled in the art to practice the invention. The two sets of levers are provided on each side of the gate in order that the tread bars may be of such length as to extend to positions near the gate so that the tread bars may serve to retain the gate in an open position until the weight

of the car is removed from them. The operating levers, which are closely associated with the cross ties, may be protected from the accumulation of foreign substances by housings, and thus the operating of the mechanism will not be impaired by such accumulations, the said housings being illustrated in Figs. 6 and 7, and they may be modified to suit particular requirements.

I claim:

1. In a mine door operating mechanism, a door mounted to guard a track, levers having their inner ends pivotally connected to a fixed object, posts carried by each of the said levers, tread bars carried by said posts and supported parallel and in close proximity to one of the rails, levers having their inner ends pivotally connected to bases, means for pivotally connecting one each of the first mentioned levers to one each of the second mentioned levers, posts connected to the second mentioned levers, tread bars supported by the posts in proximity to the other rail and projecting above the said rail, a door operating shaft, links and arms connecting the second mentioned levers with the shaft for operating the shaft, a door operating arm carried by the shaft, a link pivotally connected to the door, an arm to which the link is pivotally connected, means for oscillatably mounting the last mentioned arm, a bracket carried by the last mentioned arm, and means for pivotally connecting the second mentioned arm to the last mentioned arm for communicating the motion of the shaft to the gate.

2. In a mine door operating mechanism, a door mounted to guard a track, levers having their inner ends pivotally connected to a fixed object, posts carried by each of the said levers, tread bars carried by said posts and supported parallel and in close proximity to one of the rails, levers having their inner ends pivotally connected to bases, posts connected to the second mentioned levers, tread bars supported by the posts in proximity to the other rail and projecting above the said rail, means for pivotally connecting one each of the first mentioned levers to one each of the second mentioned levers, a door operating shaft, links and arms connecting the second mentioned levers with the shaft for operating the shaft, a door operating arm carried by the shaft, a link pivotally connected to the door, an arm to which the link is pivotally connected, means for oscillatably mounting the last mentioned arm, a bracket carried by the last mentioned arm, yokes extending inwardly from and attached to the shaft when the gate is closed and weights carried by the said yoke, and means for pivotally connecting the second mentioned arm to the last mentioned arm for communicating the motion of the shaft to the gate.

WILLIAM KORTKAMP.
